UNITED STATES PATENT OFFICE

162,406

REED MOUTHPIECE

Harold Grossman, St. Louis, Mo., assignor to Jay V. Zimmerman, Clayton, Mo.

Application December 7, 1949, Serial No. 6,465

Term of patent 7 years

(Cl. D56—1)

To all whom it may concern:

Be it known that I, Harold Grossman, a citizen of the United States, residing at the city of St. Louis, State of Missouri, have invented a new, original, and ornamental Design for a Reed Mouth Piece, of which the following is a specification, reference being made to the accompanying drawing forming a part thereof, in which—

I claim:

The ornamental design for a reed mouth piece, substantially as shown.

HAROLD GROSSMAN.
